US00D648554S

(12) **United States Design Patent**
Smith

(10) **Patent No.:** **US D648,554 S**
(45) **Date of Patent:** **** Nov. 15, 2011**

(54) **MESH STACKING CHAIR**(75) Inventor: **Richard D. Smith**, Spanish Fork, UT (US)(73) Assignee: **Mity-Lite, Inc.**, Orem, UT (US)(**) Term: **14 Years**(21) Appl. No.: **29/346,705**(22) Filed: **Nov. 4, 2009**(51) LOC (9) Cl. **06-01**(52) U.S. Cl. **D6/368**(58) Field of Classification Search **D6/335, D6/368, 347, 346, 500-502; 297/16.1, 34, 297/55-59, 239, 248, 301.3, 303.3, 448.4, 297/452.1, 452.53**

See application file for complete search history.

(57) **CLAIM**

The ornamental design for the mesh stacking chair, as shown and described.

DESCRIPTION

FIG. 1 is a front perspective view of the mesh stacking chair in accordance with my invention;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines showing is included for the purpose of illustrating environment and forms no part of the claimed design.
